Primary Examiner — Khawaja Anwar(74) *Attorney, Agent, or Firm* — Andrew F. Young; Nolte Lackenbach Siegel(57) **CLAIM**

The ornamental design for a portable label printer, as shown and described.

DESCRIPTION

FIG. 1 is a first top rear perspective view of a portable label printer showing our new design.

FIG. 2 is a second top front perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a right side elevation view thereof; and,

FIG. 8 is a left side elevation view thereof.

The dash-dot disclaim lines indicate disclaimed portions which form no part of the claimed design and the dashed-dot-dashed lines denote the boundary of the claimed design and form no part thereof.
